UNITED STATES PATENT OFFICE.

WILLIAM FRANCIS HARPER, OF MEMPHIS, TENNESSEE.

CARD-FILING APPARATUS.

1,245,713.

Specification of Letters Patent.

Patented Nov. 6, 1917.

Application filed May 16, 1916. Serial No. 97,838.

To all whom it may concern:

Be it known that I, WILLIAM FRANCIS HARPER, a citizen of the United States, residing at Memphis, Shelby county, and 5 State of Tennessee, have invented and discovered certain new and useful Improvements in Card-Filing Apparatus, of which the following is a specification.

The present invention relates to apparatus 10 for filing index cards, or the like, and consists in the combinations and arrangements of parts hereinafter described and particularly set forth in the accompanying claims.

The purpose of the invention is to provide 15 a card holding receptacle wherein the cards are collected in a neat, compact form and readily accessible for individual inspection, and in which the cards may be separately placed and removed.

20 A further purpose of the invention consists in providing a holder for filing signature cards in banks, in which the cards are grouped under the usual initial headings and in such a manner that the respective card 25 groups may be readily brought into position for handling, and the cards thereof conveniently held separated without the employment of spacing devices or "finders".

The invention is described by way of 30 illustration in the accompanying drawing, wherein:

Figure 1 is a side elevational view of the apparatus complete,

Fig. 2 an end view thereof, with the card 35 holders removed,

Fig. 3 an enlarged detail view, partly in section, showing the connection between the card holder and carrier,

Fig. 4 a detail perspective view of one of 40 the card holders, and

Fig. 5 a sectional view of a detail of the carrier.

Referring to the construction in further 45 detail and wherein like reference characters indicate corresponding parts, the apparatus consists of a supporting frame 1, having suitable bearings 2 for journaling the shaft 3 of the drum 4 that carries the several card holding frames. The means for mounting 50 the card holders on the drum 4 consists of a rim or band 5 that is supported thereon by a plurality of radially disposed spacing members 6 (see Fig. 5), or in any other suitable manner.

55 A plurality of card supporting frames 7,

constructed preferably of sheet metal, are provided for holding the individual cards on the drum, and said card frames 7 have their respective upper and lower edges turned inwardly, as at 8 and 9, to form 60 grooves for receiving the cards and permitting of their convenient removal. The lower edge 10 of each card frame is constructed with extended portions 11 that are bent as at 12 to provide bearings for the rod or pin 65 13 that passes therethrough and through the underside of the band 5 of the drum, after the manner shown in Fig. 3. The pin 13 has a head 14 that stops against one end of the pin bearing 12, and by means of this 70 head said pin is adapted to be conveniently withdrawn to remove the frame 7 to insert a new card.

The card carrying frame is adapted to be conveniently rotated on its axis, for bringing 75 the desired card group into position for inspection or handling, by a pair of side frames that may be conveniently engaged. The frames consist of a pair of annular rods 15 disposed on either side of the card frames, 80 and which are secured to the walls 4^a of the drum by the radially disposed bars 16, as clearly shown in Figs. 1 and 3.

It will be seen from the foregoing that with having all the cards of the system arranged 85 in circular formation, economy of space is obtained, and that any desired group of cards may be conveniently brought into position for inspection or handling; and that the individual card frames may be 90 moved by sliding on the drum, and, further, that the card frames will remain in separated position (see Fig. 1) without requiring the use of blocks or other spacing devices which are usually employed to mark 95 locations in the present system of card filing.

It is obvious that those skilled in the art may vary the details of construction and arrangement of parts without departing from 100 the spirit of my invention, and therefore I do not wish to be limited to such features except as may be required by the claims.

Having thus fully described my said invention, what I claim as new and desire to 105 secure by Letters Patent, is:

1. An apparatus for filing index cards comprising a rotatable drum, an annular band mounted on the drum and radially spaced therefrom, a plurality of card hold- 110

ing frames, and rods for detachably mounting said card holding frames to slide on said annular band, substantially as set forth.

2. An apparatus for filing index cards comprising a rotatable drum, an annular band mounted on said drum and radially spaced therefrom, a plurality of card holding frames constructed of sheet metal and having bearing members, and rods passing through said bearing members and under said band detachably mounting said frames to slide on the band, substantially as set forth.

3. An apparatus for filing index cards comprising a rotatable drum having an annular portion radially spaced therefrom, a plurality of card holding frames, rods for

detachably mounting said card holding frames to slide on said annular portion, a plurality of radially disposed bars secured to the drum on either side of said annular portion, and a pair of annular rods secured to said radial bars and therewith providing hand-gripping devices for turning the drum, substantially as set forth. 20 25

In witness whereof, I have hereunto set my hand and seal at Memphis, Tennessee, this 12th day of May, A. D. nineteen hundred and sixteen.

WILLIAM FRANCIS HARPER. [L. S.]
